ATTORNEY

UNITED STATES PATENT OFFICE.

AUGUST T. NISWANGER, OF SEATTLE, WASHINGTON.

POST-HOLE-DRILLING MACHINE.

Specification of Letters Patent. Patented Feb. 25, 1919.

1,295,574.

Application filed March 28, 1918. Serial No. 226,115.

To all whom it may concern:

Be it known that I, AUGUST T. NISWANGER, a citizen of the United States, residing at Seattle, in the county of King and State of Washington, have invented a new and useful Improvement in Post-Hole-Drilling Machines, of which the following is a specification.

This invention relates to improvements in post hole drilling machines, and the object of this improvement is to provide a machine that can be manually actuated to drill post holes very quickly through a rotary process.

A further object resides in adaptability of the drilling mechanism to swing to various positions on the frame for boring operations.

A still further object resides in the adaptability of the machine to be moved from place to place without having to be dismantled, and in the adjustability of the supporting legs to maintain the drilling mechanism in a level plane.

Further objects will appear from the following specification, illustrated in the accompanying drawings and finally pointed out in the appended claims.

In the drawings, Figure 1 is a plan view of the machine; Fig. 2 is a side elevation thereof; Fig. 3 is a view in elevation of a detail of the drilling mechanism; Fig. 4 is a detail of an adjustable supporting stabilizer for the drilling mechanism; Fig. 5 is a detail of the clutch actuating lever; and Fig. 6 is a side elevation showing the application of the adjustable wheels to the frame of the machine.

Referring more particularly to the drawings, in which like reference numerals indicate like parts, the numeral 1 represents the frame of the machine supported upon extension legs 2, and these legs are adapted to be extended to various adjustable positions by set screws 3. Disposed intermediate the upper and lower parts of the frame 1 are integrally connected gears 4 sometimes known as "Siamese gears," and these gears are disposed for longitudinal movement upon a rotatable shaft 5 vertically mounted upon the frame 1.

6 is a plate disposed upon the upper face of the frame 1 and this plate is projected outwardly from the frame to one side thereof and has attached thereto a supporting stabilizer 7 adapted to make contact with the ground and adjustable in length by means of a set screw 8.

Superimposed upon this plate 6 in bearing contact therewith is the gear 9 which is fixedly secured to the shaft 5 for rotation therewith, and above this gear is disposed the member 10 which is supported rigidly upon the plate 6 by position bolts 11.

12 is a threaded bar mounted for rotation through the outer projection of the member 10 and plate 6, and upon the lower end of this threaded bar is attached an auger 25 in any well known manner.

Disposed intermediate the plate 6 and the member 10 is a gear wheel 13 keyed for longitudinal movement upon the threaded bar 12, and this gear wheel is adapted to be in meshing contact with the gear 9 whereby, when the shaft 5 is rotated, the threaded bar 12 will be rotatably actuated to move up and down through its meshing contact with the threaded slots in the plate 6 and member 10 through which it protrudes.

14 is a shaft rotatably mounted through the side of the frame 1 and upon the end of this shaft is fixedly secured a beveled pinion 15 intermediate the adjacent faces of the integrally connected gears 4 with which it is adapted to alternately engage in meshing contact, and upon the outer end of the shaft 14 is provided a fixedly secured pulley 16 having a handle 17 attached thereto transversely thereof upon its outer periphery.

18 is a lever pivotally attached to a bracket 19 projecting downwardly from the frame 1, one end of the lever being formed into a yoke 20 and adapted to pivotally engage the opposite sides of the hub of the integrally connected gears 4, and the other end of the lever being formed with a handle 21 and having pivotally attached thereto a pin 22 for engaging a slot 23 provided in the lower part of the upper frame 1, and this pin is yieldingly actuated to engage this slot by a compression spring 24 interposed between the lever handle 21 and the handle portion of the pin 22 whereby the actuation of the lever 18 will shift the integrally connected gears 4 longitudinally upon the shaft 5 to engage alternately the beveled pinion 15, the pin 22 being herein adapted to hold the lever 18 in contact with the frame and thus retain the integrally connected gears 4 stationary upon the shaft 5 in one of its shifted positions, with the beveled pinion 15 in contact with one of its adjacent faces.

In recognition of the fact that the drilling mechanism must be frequently shifted

- after each boring operation, provision has been made for shifting the drilling mechanism to assume various positions around the sides of the frame without having to shift the position of the frame. This function is obtained by disengaging from frictional contact the cam pin 26 with the sides of the slotted channel 27 provided around the outer periphery of the plate 6, thereby permitting the superimposed mechanism upon the frame 1 to be shifted to various positions confined to the radius of the circular channel from the shaft 5, which constitutes the pivotal point of contact.
- 28 is a pivotally mounted truck frame attached to brackets 29 extended downwardly from the lower frame 1 of the machine on one side thereof, and upon the ends of this truck frame are provided rotatably mounted wheels 30, the balance of the truck frame at the pivotal point being such that the wheels will be automatically elevated clear of the ground when pressure has been removed from the elongated ends thereof.
- It is obvious that provision of these wheels will provide means for easily moving the machine over the ground without having to disassemble and reassemble the machine at the various places of operation.
- It is to be understood that many mechanical changes can be made in the details of construction within the scope of the following claims.

What I claim as new, and desire to protect by Letters Patent, is:—

1. A post hole drilling machine comprising a frame structure, a shaft rotatably mounted upon said frame structure, reversible means for rotating said shaft, means superimposed upon said frame and supported from the ground at one side thereof, a threaded bar, a pinion thereon co-operating with said means for actuating said bar upwardly and downwardly, an auger attached to the lower end of said bar and a gear wheel fixedly secured to said shaft and adapted to actuate said pinion, whereby said auger can be caused to penetrate the ground and be removed therefrom.
2. A post hole drilling machine comprising a frame structure, a shaft rotatably mounted upon said frame structure, integrally connected gears keyed for longitudinal movement upon said shaft, a beveled pinion adapted to mesh alternately with said integrally connected gears, a lever for actuating said integrally connected gears to move longitudinally upon said shaft to establish forward and reverse speed, thread-

ed means superimposed upon said frame and supported from the ground at one side thereof, a threaded bar received therein and an auger therefor, a gear wheel keyed for longitudinal movement upon said threaded bar, a gear fixedly secured to said shaft in meshing contact with said gear wheel whereby said auger can be caused to penetrate the ground and be removed therefrom. 65

3. A post hole drilling machine comprising a frame structure, a shaft rotatably mounted upon said frame structure, a beveled pinion adapted to be manually actuated, integrally connected gears keyed for longitudinal movement upon said shaft, a lever for actuating said gears to alternately engage said beveled pinion to establish forward and reverse speeds, threaded means superimposed upon said frame and supported from the ground at one side thereof, a threaded bar received therein and an auger therefor carried by said means, a gear wheel keyed for longitudinal movement upon said threaded bar, a gear fixedly secured to said shaft in meshing contact with said gear wheel, whereby said auger can be caused to penetrate the ground and be removed therefrom, and means for shifting the drilling mechanism superimposed upon said frame around the sides thereof. 70 80 85

4. A post hole drilling machine comprising a frame structure having legs adjustable in length with respect thereto, a shaft rotatably mounted upon said frame structure, a beveled pinion adapted to be manually actuated, integrally connected gears keyed for longitudinal movement upon said shaft, a lever for actuating said gears to alternately engage said beveled pinion to establish forward and reverse speeds, threaded means superimposed upon said frame and supported from the ground at one side thereof, a threaded bar received therein and an auger therefor carried by said means, a gear wheel keyed for longitudinal movement upon said threaded bar, a gear fixedly secured to said shaft in meshing contact with said gear wheel, whereby said auger can be caused to penetrate the ground and be removed therefrom, means for automatically supporting the weight of said machine upon wheels, and means for shifting the drilling mechanism superimposed upon said frame around the sides thereof. 90 95 100 105 110

Signed by me at Seattle, Washington, this 19 day of March, 1918.

AUGUST T. NISWANGER.
